UNITED STATES PATENT OFFICE.

WALTER SANDBERG, OF PORTLAND, OREGON.

AUTOMATIC WINDOW-SCREEN.

1,329,929.

Specification of Letters Patent. Patented Feb. 3, 1920.

Application filed October 30, 1919. Serial No. 334,453.

To all whom it may concern:

Be it known that I, WALTER SANDBERG, a citizen of the United States, residing at Portland, in the county of Multnomah and State of Oregon, have invented a new and useful Automatic Window-Screen, of which the following is a specification.

My invention relates to improvements in automatic window screens in which a 10 appearing screen is attached to the lower window sash inside the house.

The objects of my invention are, first, to furnish a screen which makes it almost impossible for children to fall out of the window; second, to give the screen and its machinery a longer life by placing it inside the house; third, to provide a screen which can easily be separated from the sash, yet is always near at hand when required; fourth, 20 to avoid the inconvenience attendant to screens which are attached to the outside of a house.

I attain these objects with the mechanism shown in the accompanying drawing, in 25 which:—

Figure I is a front elevation of the lower part of a window as seen from the inside of the house, with the machinery properly incased; the construction on the right hand 30 side, however, is a modification of the one shown on the left hand side.

Fig. II is a section of Fig. I along the line *a—a*, but with the protective casing omitted.

Fig. III is a section of Fig. I along the 35 line *b—b*, disclosing fully the construction of the most essential parts.

Fig. IV is a section through Fig. I along the line *c—c*, revealing a slight modification of the apparatus shown in Fig. II.

Similar numerals refer to similar parts 40 throughout the several views.

Referring now particularly to Fig. III, we notice a window sash 1 of vertically-sliding construction resting on the window-sill 2 45 and held in its place by the window stops 3.

It will be noted, however, that the stop at the inside of the house is provided with a vertical groove 4, and that a wire screen 5 which extends over the entire width of the 50 window terminates in said groove. This wire screen is rigidly attached to a Z-bar 6, which latter in turn is removably hung to the screws 7 on the window sash 1. A raising of the sash will also raise the screen; 55 and the rowels 8, by pressing into the meshes, will make lateral motion of the

screen impossible. A roller 9 of small diameter and suitably supported within the window stop 3 assists in leading the screen 5 properly into the groove 4. A roller 10 60 of somewhat larger diameter winds and unwinds the screen as the window sash 1 is raised or lowered.

Since, however, the screen would not wind upon the roller of its own accord, I connect 65 one or both ends of the large roller 10 with a train of gears 11; which latter tighten a spiral spring 12 whenever the screen is unwound. This spiral spring in turn will react and produce the necessary torsion on 70 the large roller to wind the screen when the sash is lowered.

The protective casing over the gearing is indicated by the numeral 13.

A reference to Fig. II will fully illustrate 75 any details of construction which are not obvious from the Fig. III alone; and it only remains to point out the modification pictorially represented in Fig. IV.

Here we find practically a repetition of 80 every essential detail previously described, except that the train of gears 11 is not composed of spur gears only, but that one of them, preferably 11^a, which carries the spiral spring 12, is a crown gear, so that this 85 part of the gear may be located around a corner. This construction is desirable where the window sill is narrow and can not accommodate a full series of spur gears. In their effect upon the screen 5, however, both 90 mechanisms are identical.

Numeral 14, it might be added, indicates the handles on the Z-bar, to lift the latter on and off the screws 7 on the sash 1.

Having thus described my invention, it 95 will be seen that my objects have been accomplished, and, though I have shown the preferred form of construction, I reserve to myself the right to make any changes which do not violate the spirit and principle of 100 my invention.

I claim:

1. In an automatic window screen, the combination of a window having a sill, a vertically sliding sash, and having a vertically grooved stop to guide said sash, with a wire screen disappearingly mounted on the window sill, having the upper end removably attached to the lower part of the sash and sliding with the lateral edges within 105 the vertical groove of said stops.

2. In an automatic window screen, the

combination of a window having a sill and a vertically sliding sash, having grooved stops to guide the interior face of the sash, and having a plurality of rowels extending into the grooves, with a window screen dis-
5 appearingly mounted on the window sill, a removable Z-bar to keep the wire screen in

sliding alinement with the grooves in the stops, while the rowels enter into the lateral edges of said screen and prevent a disen- 10 gagement of said edges from said grooves.

Signed by me at Portland, Oregon, this
24th day of October, 1919.

WALTER SANDBERG.
